UNITED STATES PATENT OFFICE.

JAMES W. GAITHER, OF MARTIN'S FERRY, OHIO.

DESIGN FOR A GLASS VESSEL.

SPECIFICATION forming part of Design No. 24,785, dated October 22, 1895.

Application filed August 6, 1895. Serial No. 558,426. Term of patent 14 years.

To all whom it may concern:

Be it known that I, JAMES W. GAITHER, of Martin's Ferry, in the county of Belmont and State of Ohio, have invented a new and original Design for Vessels of Glassware, of which the following is a full, clear, and exact description, reference being had to the accompanying drawing, which shows in side elevation a glass vessel embodying my design.

The design consists in a vessel of glassware having a surface with frosted appearance ornamented with superimposed raised opaque figures, substantially as herein shown and described.

In the drawing, 2 represents a vessel of glass-

ware, the surface of which has a frosted appearance, and 3 are raised opaque figures on the exterior surface of the vessel. The raised prominent character of the figures 3 on the surface of the vessel is an essential element 20 of my design.

I claim—

The design for vessels of glassware substantially as herein shown and described.

In testimony whereof I have hereunto set 25 my hand.

JAMES W. GAITHER.
